[57] CLAIM

The ornamental design for a seat for agricultural vehicle, as shown and described.

DESCRIPTION

FIG. 1 is a top view of one embodiment of a seat for agricultural vehicle;

FIG. 2 is a left side view of the seat shown in FIG. 1;

FIG. 3 is a right side view of the seat shown in FIG. 1;

FIG. 4 is a front view of the seat shown in FIG. 1;

FIG. 5 is a rear of the seat shown in FIG. 1;

FIG. 6 is a bottom view of the seat shown in FIG. 1;

FIG. 7 is a top view of a second embodiment of a seat for agricultural vehicle;

FIG. 8 is a bottom view of the seat shown in FIG. 7;

FIG. 9 is a left side view of the seat shown in FIG. 7;

FIG. 10 is a right side view of the seat shown in FIG. 7;

FIG. 11 is a front view of the seat shown in FIG. 7; and,

FIG. 12 is a rear view of the seat shown in FIG. 7.

The broken lines showing hand grips on the safety bow are for illustrative purposes only, and do not form a part of the claimed design.
